(57) **CLAIM**

The ornamental design for a wall light as shown and described.

DESCRIPTION

FIG. 1 is a front perspective view of a wall light showing my new design;

FIG. 2 is a rear perspective view thereof;

FIG. 3 is a rear perspective view in another angle thereof; FIG. 4 is a front elevational view thereof, the rear elevational view being a mirror image of FIG. 4;

FIG. 5 is a left side view thereof;

FIG. 6 is a right side view thereof;

FIG. 7 is a top plan view thereof;

FIG. 8 is a bottom plan view thereof;

FIG. 9 is a front perspective view of the wall light in a detached state; and,

FIG. 10 is a rear perspective view of the wall light in a detached state.

The broken lines in the figures are for the purposes of illustrating portions of the wall light, which form no part of the claimed design.

1 Claim, 8 Drawing Sheets
